TERRESTRIAL GLOBE MOUNTING

Arthur L. Peterson, Indianapolis, Ind., assignor
to The Geo. F. Cram Company, a corporation
of Illinois

Application March 26, 1938, Serial No. 198,191

4 Claims. (Cl. 35—46)

My invention relates to improvements in terrestrial globes and particularly to that type of terrestrial globes which are mounted within a meridian ring.

5 It is one of the objects of my invention to provide a terrestrial globe and meridian ring so mounted that the globe itself may more readily be observed than the types of globes now used.

Another object of my invention is to provide 10 a mounting for terrestrial globes and its accompanying meridian ring, whereby the meridian ring may be more readily seen and read than has heretofore been the case particularly with the globe inclined on its polar axis.

15 Heretofore, particularly in the commercial art, the terrestrial globes have been so mounted in their meridian ring that it has been inconvenient and, to a large extent, impracticable to observe the parallels of latitude with the graduate lines or indications on the meridian ring.

It is one of the objects of my invention to provide a mounting for the meridian ring and globe so that the above objections may be overcome.

25 For the purpose of disclosing my invention, I have illustrated the embodiments thereof in the accompanying drawing, in which:

Fig. 1 is an elevation of a terrestrial globe and its stand embodying my invention;

30 Fig. 2 is a detail section showing the manner of mounting the globe;

Fig. 3 is an enlarged front elevation of a portion of the globe mounting; and

Fig. 4 is an elevation of a globe similar to that 35 illustrated in Fig. 1, except that interior illumination for the globe is provided.

In the embodiment illustrated, having particular reference to Figs. 1, 2 and 3, I provide a stand 1 which may be formed of sheet metal 40 or other like material, having an upwardly extending center pedestal 2. Laterally extending from this pedestal is an arm 3 which is preferably slightly curved to conform to the curvature of the globe and the globe and its associated meridian ring are mounted at the outer end of this arm. In the structure illustrated, 45 the globe 4 is mounted within the meridian ring 5, a north pole pivot pin 6 being provided in the top of the meridian ring for penetrating

50 an opening in the top of the globe to provide a support at this end. The meridian ring 5, at its lower end, is provided with an enlarged boss 7 internally screw threaded to thread on to an upwardly extended threaded bolt 8 mounted 55 at the end of the arm 3. This bolt extends

upwardly through the meridian ring and projects into a south polar opening in the globe 4 so that in mounting the parts, the globe may be first inserted in the meridian ring receiving the north polar pin 6 and the meridian ring, 5 then screw threaded on to the pin or bolt 8, the bolt projecting through the south polar opening in the globe. By this arrangement, the globe and meridian ring are both held in proper assembled position. With the bolt 8 screwed up 10 tight into the enlarged boss 7 in the meridian ring 5, the meridian ring is securely clamped upon the arm 3 and held in fixed position against rotation on the arm so as to maintain the ring against rotation on the polar axis of the globe 15 and in the position illustrated in the drawing.

The assembly is such that the meridian ring lies in a plane having an inclination coincident with the polar axis of the globe. Therefore, with the structure placed upon a desk or other 20 stand, it will be observed that the side 9 of the globe and the side of the meridian ring are presented in such position as to be more readily observed than would be the case if the globe was arranged vertically or if the globe was arranged with the meridian ring as is usual. The 25 globe and the meridian ring are mounted to be presented to the reader in much the same manner as a book or other article is placed upon a reading desk, with the portions of the globe 30 with the indicia on the meridian ring more directly in line with the vision of the observer.

Furthermore, it will be noted that, due to the fact that the meridian ring is arranged in a plane inclined coincidentally with the polar axis 35 of the globe, the sides of the meridian ring, particularly one side thereof, are in a position to be more readily observed by the observer than is usually the case and the parallels of latitude may readily be read in connection with the indicia 40 which are formed on the sides of the meridian ring.

In Fig. 4, I have illustrated a modification of the structure illustrated in Fig. 1 wherein the parts are mounted in the same assembled relation except in this instance the globe is carried, at its bottom, on a supporting disc 10 fixed to the meridian ring and there is mounted on the meridian ring, in such a manner as to project within the globe, a lamp socket 11 adapted to 45 receive an illuminating lamp 12. Likewise, in this structure, the globe itself may be formed of translucent material.

I claim as my invention:

1. A terrestrial globe comprising a globe adapt- 55

ed to be supported to rotate on its polar axis, a stand, a globe supporting ring mounted on said stand, normally held against rotation on the polar axis of the globe and arranged in a plane inclined at an angle coincident with the polar axis of the globe and a terrestrial globe, mounted within said meridian ring and supported to rotate on its polar axis.

2. A terrestrial globe comprising a globe adapted to be supported to rotate on its polar axis, a stand, a supporting arm extending laterally from said stand, a globe supporting ring mounted on said arm and normally held against rotation on the polar axis of the globe and arranged in a plane inclined at an angle coincident with the polar axis of the globe, and a terrestrial globe mounted within said meridian ring and supported to rotate on its polar axis.

3. A terrestrial globe comprising a globe adapted to be supported to rotate on its polar axis, a

stand, a globe supporting meridian ring mounted on said stand and normally held against rotation on the polar axis of the globe, arranged in a plane inclined at an angle coincident with the polar axis of the globe and having indicia on its upper face, and a terrestrial globe mounted within said ring and supported to rotate on its polar axis.

4. A terrestrial globe comprising a globe adapted to be supported to rotate on its polar axis, a stand, a globe supporting meridian ring mounted on said stand normally held against rotation on the polar axis of the globe and arranged in a plane inclined at an angle coincident with the polar axis of the globe, the upper face of said ring being flattened and having indicia thereon, and a terrestrial globe mounted within said meridian ring and supported to rotate on its polar axis.

ARTHUR L. PETERSON. 20
